UNITED STATES PATENT OFFICE.

HARRY C. H. WALSH, OF CHICAGO, ILLINOIS.

DIAL FEED.

Application filed June 14, 1922. Serial No. 563,160.

My invention relates to improvements in dial feeds and has particular reference to step-by-step feed devices such as may be used in connection with machines for operating upon like pieces of work, for instance, punch presses.

The principal objects of the invention are to provide an improved feed device so arranged that it will accurately and positively 10 position each piece of work in the field of the operative machine; to provide a construction so arranged that the position of each work support may be utilized as a means for laying out the register mechanism, thereby insuring absolute accuracy of register regardless of slight variations in the spacing of the work supports; to provide an improved arrangement of the step-by-step type in which the positioning of the 15 work supports is within proper limits independent of the amount of motion imparted to the feed device by the step-by-step mechanism; to provide an improved arrangement in which the operating parts are substantially covered, thereby preventing damage by abuse or by ingress of foreign material; to provide a construction which shall be 20 neat, compact and simple in design and readily applicable to machines of standard 25 design; to provide an arrangement having comparatively few operating parts and those of simple and rugged character; to provide an arrangement which shall be comparatively inexpensive to manufacture, maintain 30 and operate while being convenient to install, repair, adjust and manipulate, and in general to provide an improved efficient feed 35 device of the character referred to.

In the drawings which illustrate my improved feed device as applied to a punch 40 press,

Fig. 1 is a side elevation of the punch press equipped with my device;

Fig. 2 is a plan view of the feed device;

Fig. 3 is a left hand side elevation of the device shown in Fig. 2;

Fig. 4 is a section taken on the line 4—4 of Fig. 2;

Fig. 5 is a section taken on the line 5—5 50 of Fig. 2;

Fig. 6 is a section taken on the line 6—6 of Fig. 2, and

Fig. 7 is a section taken on the line 7—7 55 of Fig. 2.

Referring to the drawings, it will be observed that the punch press is constructed

in the ordinary manner with a base casting 10, a tilting frame 11, fly wheel 12 and main crank shaft, which shaft is capable of being clutched to the constantly rotating fly wheel 12 by any desired conventional form of clutch mechanism (not shown). On the end of the crank shaft 13, there is keyed a crank disc 14 having a crank pin 15 adjustably connected to the end of a connecting rod 16. 65 The connecting rod 16 hence reciprocates whenever the crank shaft 13 of the punch press is rotated for the purpose of reciprocating the cross head 17.

As applied to the particular machine disclosed, the carrier of the feed device takes the form of a disk or dial 18 mounted to rotate on a vertical axis. The dial 18 is made with a plurality of work supports, which, in the present instance are shown as ordinary 70 circular apertures as at 19 in which the pieces of work are inserted by the operator and after travelling around the machine and being subjected to the action of the operative tools of the machine such as the punch 20 and die 21, are subsequently removed from the dial to permit the insertion of new work. Such removal may be performed manually 75 or automatically as dictated by circumstances. It will be understood that the purpose of the device is to successfully bring the work supports into position so that the work on same will be positively and accurately registered in the operative field of the machine and held in such position for a sufficient 80 length of time to enable the punch to reciprocate and perform the desired operation on the work.

As shown best in Figs. 5 and 6, the dial 18 is rigidly secured, as by cap screws 22 to 85 the back face of the bevel gear 23 having its teeth presented facing downwardly. The bottom surface of the dial 18 is supported by and rotatably slides on a base casting 24, which casting is drilled out vertically to 90 form a support for the fixed vertical stud or pin 25 preferably a press fit in casting 24. The bushing 26 is a running fit on the upper end of stud 25 and is a press fit in gear 23 and dial 18, said three parts revolving as a 100 unit on pin 25.

The upper end of the stud 25 is threaded to receive a nut 27 between which nut 27 and the upper surface of dial 18 there is interposed an upper steel washer 28 and an intermediate fiber thrust washer 29. The steel washer 28 is prevented from rotating 110

on the pin 25 by means of a Woodruff key 30 while the fiber washer 29 may or may not rotate, depending upon whether the friction on the surface of dial 18 or the surface of fixed washer 28, is the greater. Nut 27 serves to hold dial 18 with its lower surface in intimate contact with the upper surface of base casting 24, thereby preventing separation of the sliding surfaces and eliminating shake and ingress of foreign matter.

Below the level of the dial 18 the bed plate 24 is made with a lateral extension comprising an integral part 31 and a part 32 secured to the face of extension 31 by means of bolts 33. Said extension parts are cored out to admit a horizontal shaft 34 the inner end of which is rotatably supported in a bearing 35, and the outer end in a bearing 36. On the inner end of said horizontal shaft 34 there is keyed a bevel pinion 37 located in a recess 38 and meshing with the bevel gear 23 previously referred to. On the outer end of the shaft 34 there is keyed a ratchet wheel 39 and on the opposite sides of ratchet wheel 39 and loosely journaled on the end of shaft 34 there are two oscillating arms or levers 40 and 41. Preferably the lever 41 is enlarged as shown at 42 in order to conceal and protect the ratchet mechanism. The arms 40 and 41 are connected to move as a unit by pins or bolts 43, 44 and 45. Reciprocatory motion is imparted to the pair of arms 40 and 41 by means of the connecting rod 16 the lower end of which is enlarged and drilled out to pivotally connect with the pin 43.

On the pin 44 there is pivotally mounted a pawl 45^a which is arranged to engage with the ratchet teeth 46 on ratchet wheel 39, said pawl 45^a being held up to its work by means of a small coiled compression spring 47 having its ends seated in recesses formed respectively in the back of pawl 45^a and in the face of a lug 48 formed on the arm 41. Retrograde movements of the ratchet wheel 39 are prevented by a retaining pawl 49 pivotally carried by a fixed pin 50 secured in an aperture horizontally drilled in an up-standing lug 51 on the end of extension casting 32.

In order to facilitate adjustment of the retaining pawl 49, the pin 50 is made with an eccentric enlargement 52 whereby, upon rotation of said pin enlargement 52 in lug 51, the point of pawl 49 can be advanced or retracted circumferentially around ratchet wheel 34. When the proper adjustment has been established, pin 52 may be locked in position by set screw 53.

It will be manifest that as the punch press operates, the reciprocation of rod 16 will cause intermittent step-by-step rotary movements of the shaft 34 which will result in corresponding step-by-step rotary movements of the carrier dial 18. Obviously, the

angular spacing between the work support openings 19 correspond with each step-by-step movement of said dial. If mechanical perfection could be reached, and if there were no inertia of the moving parts, it might be possible to operate the dial feed without further provision for exact register between the position of the punch and die and the location of the work supports as successively moved into the operating field of said punch and die. However, I have found that because of mechanical and shop practice limitations and because of the inertia of the parts, it is necessary in most cases to provide further special means for insuring a more perfect register between the punch and die and the successive work supports. To this end, I employ the following arrangement. After the openings or work supports 19 on the dial have been laid out and finished up as accurately as is desired or practical under the circumstances, each of the work supports or openings 19 is utilized as a guide or jig for the purpose of laying out and drilling its corresponding registering part, in this instance one of the dowel openings 53^a. Since the center of the stationary dowel position is represented by numeral 54, and the operating center of the punch and die is represented by numeral 55, it is merely necessary to provide that the angle A shall be accurate as to each of the dowel holes 53 and its corresponding work support.

The dowel pin 56 slidably reciprocates in a cylindrical bore 57 drilled vertically into casting 24, the upper end of the dowel pin being slightly rounded or tapered as shown at 58 so that it will find its way into the dowel hole in spite of considerable variation of position or lack of register of the dial.

Intermediate its ends, the bore 57 is cut out at the side to make room for an oscillating arm or finger 59, the outer end of which is rounded as indicated at 60 to engage the edges of a rectangular notch cut in the side of dowel pin 56. Arm 59 is keyed on the end of a horizontal shaft 61 extending under a flanged cover 62 formed integral with the extension part 32. The shaft 61 is mounted to rock or pivot on a pair of adjustable centers 63 and 64 mounted in lugs 65 and 66, said type of pivotal mounting being selected in order to reduce friction to a minimum while enabling accurate adjustment of the shaft to be made. On the outer end of the rock shaft 61 there is keyed a dog 67 equipped with a pair of integral arms 68 and 69. Said arms 68 and 69 are suitably shaped and positioned as to be engaged at the proper time by a roller 70 on pin 45, when the arms 40 and 41 are reciprocated by rod 16. In conjunction with the dog 67 and roller 70, the rocking action of rock shaft 61 is controlled by a "cross-the-center-spring" mechanism.

115
120
125
130

Said cross-the-center-spring mechanism is arranged to rock or oscillate around the center of a horizontal pin seated in an aperture drilled in the base plate extension 31. Pin 71 is a running fit and is held in position longitudinally by a vertical pin 72 engaging in a groove 73 circumferentially formed around said pin 71. On the projecting end of said pin 71 there is formed a head 74 to which is suitably united a tubular lateral extension 75. The head 74 and tubular portion 75 are suitably bored out to form a sliding support for a plunger 76, the outer end of which is formed with an integral wedge shaped knife edge 77 engaging a lateral notch 78 on the back side of the hub of arm 59. Said plunger 76 is forced strongly upward, i. e., toward the center of rock shaft 61, by means of a strong coiled compression spring 79 contained within the tube 75 and surrounding a tail or extension 80 on plunger 76. The strength of said spring 79 can be regulated by means of a set screw 81 and lock nut therefor 82, which set screw 81 serves to advance a small plug 83 slidably contained in the rear of tube 75 and against which the back end of the spring 79 abuts.

In view of the above detailed description of the mechanism, the operation of same will be apparent to those skilled in the art. It will be understood that the downward or advancing stroke of the rod 16 occurs during that portion of the revolution of the press crank shaft when the punch and die or other operative tool is out of engagement with the work so that the dial may revolve without interference. When the rod 16 descends, the pawl 45^a engages one of the ratchet teeth 46 and rotates the shaft 34 one notch, pawl 49 preventing the shaft from being retracted. Just before the ratchet wheel 39 completes its movement, the roller 70 strikes the inner face of arm 68 and rocks the shaft 61. The rocking of shaft 61, also, by reason of the engagement of knife edge 77 with notch 78 of the hub of arm 59, causes a rocking action of stud 71 which carries the across-the-center-spring mechanism, the arrangement being such that the roller 70 turns the shaft far enough to permit the knife edge 77 to cross a center line connecting the axis of shaft 61 and axis of pin 71. As soon as this occurs, the spring 79 acts in a direction to assist continued rotation of shaft 61 which then snaps forward under the influence of the cross-the-center-spring mechanism and throws up pin 56 through the engagement of the latter by the end of arm 59. If at that time the dowel hole of the dial is slightly out of register with the dial pin 56, the tapered end 58 of said pin will nevertheless enter the dowel hole and accurately position, locate and lock the dial in proper register.

Upon the return or upward stroke of the rod 16 the roller 70 will engage the arm 69 causing a reverse rotation of shaft 61 which will cause the arm 59 to withdraw the dowel pin 56 from out of the dowel hole in the dial. Hence, on the next stroke of the machine when the dial is advanced, the dowel pin 56 will not interfere with the step-by-step movement. When the shaft 61 is thus turned to withdraw the dowel, the knife edge 77 of the cross-the-center mechanism is shifted to a position slightly across the center line, thereby holding dowel pin 56 at the bottom of bore 57 until roller 70, upon the next stroke of the press, engages the arm 68.

The described details of construction and operation are merely illustrative of a single phase of my invention, the scope of which should be determined by reference to the appended claims, said claims being construed as broadly as possible, consistent with the state of the art.

I claim as my invention:

1. In a feeding device, the combination with the operative machine, of an endless carrier provided with a series of work supports, means for intermittently advancing said carrier step by step to bring the work on said supports successively into the operative field of the machine, and register mechanism comprising a member adapted to interlock with the carrier intermediate step-by-step movements of the latter, the carrier having its cooperating interlocking parts respectively definitely located with respect to the work supports whereby the work supports will be successively registered with the machine, and actuating means for said member including across-the-center-spring mechanism controlled by the advancing means.
2. In combination, a rotary feed member, a shaft, gearing for driving the feed member from the shaft, ratchet mechanism for rotating the shaft intermittently step by step, and dowel mechanism actuated by the ratchet mechanism for positioning the feed member.
3. In combination, an axially vertical feeding dial, a horizontal shaft, beveled gearing for driving the dial from the shaft, ratchet mechanism for rotating the shaft step by step and dowel mechanism actuated by the ratchet mechanism for positioning and locking the dial.
4. In combination, an axially vertical feeding dial, a horizontal shaft, bevel gearing for driving the dial from the shaft, ratchet mechanism for rotating the shaft, doweling means actuated along with the ratchet mechanism for positioning the dial and a cross-the-center-spring mechanism for controlling the dowel.
5. In combination, a feed dial, a drive shaft therefor, bevel gearing connecting the shaft and dial, step by step mechanism for

rotating said drive shaft, a member adapted to have interlocking engagement with the dial in the successive positions of the latter, a rock shaft for controlling said member and thereby engaging and disengaging the dial and means operated by the step by step mechanism for actuating the rock shaft.

6. In combination, a feed dial, a drive shaft therefor, bevel gearing connecting the shaft and dial, step by step mechanism for rotating said drive shaft, a member adapted to have interlocking engagement with the dial in the successive positions of the latter, a rock shaft parallel with the driving shaft for controlling said member and thereby engaging and disengaging the dial and means operated by the step by step mechanism for actuating the rock shaft.

7. In combination, a feed dial, a drive shaft therefor, bevel gearing connecting the shaft and dial, step by step mechanism for rotating said drive shaft, a member adapted to have interlocking engagement with the dial in the successive positions of the latter, a rock shaft parallel with the driving shaft for controlling said member and thereby engaging and disengaging the dial and means operated by the step by step mechanism for actuating the rock shaft, and a cross-the-center-spring mechanism for locking said rock shaft in its engaged and disengaged positions.

8. In combination, a feed dial provided with a series of dowel apertures, a horizontal drive shaft, bevel gearing connecting the shaft and dial, step by step mechanism including an oscillating arm, pawl and ratchet,

for effecting step by step advancing movements of the drive shaft corresponding with the spacing of said apertures, a dowel pin 40 having its axis stationary and adapted to successively engage the said apertures to position and lock the dial, a rock shaft parallel with the drive shaft and having a finger thereon for reciprocating the dowel pin and means on said arm for rocking said rock shaft.

9. In combination, a feed dial provided with a series of dowel apertures, a horizontal drive shaft, bevel gearing connecting the shaft and dial, step by step mechanism including an oscillating arm, pawl and ratchet, for effecting step by step advancing movements of the drive shaft corresponding with the spacing of said apertures, a dowel pin 55 having its axis stationary and adapted to successively engage the said apertures to position and lock the dial, a rock shaft parallel with the drive shaft and having a finger thereon for reciprocating the dowel pin and means on said arm for rocking said rock shaft, and a cross-the-center-spring mechanism cooperating with said finger for controlling the movement of said rock shaft.

10. In a feeding device, a rotary member 65 provided with a series of apertures, means including a rock shaft for intermittently rotating said member, means for positioning said member comprising a dowel-pin adapted to be moved into one of said apertures, and means actuated by said rock shaft for so moving said dowel-pin.

HARRY C. H. WALSH.
